CLAIM

The ornamental design for a goggle frame, as shown and described.

DESCRIPTION

FIG. 1 is a perspective view of a goggle frame showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the goggle frame in condition of use, the broken lines are for illustrative purposes and form no part of the claimed design.
